UNITED STATES PATENT OFFICE

167,201

SLIPPER

Israel Garon, Duluth, Minn.

Application April 3, 1952, Serial No. 19,178

Term of patent 14 years

(Cl. D7—7)

To all whom it may concern:

Be it known that I, Israel Garon, a citizen of the United States of America, residing at Duluth, Minnesota, Saint Louis County, have invented a new, original, and ornamental Design for Slipper, of which the following is a specification, reference being had to the accompanying drawing, forming a part hereof.

Fig. 1 is a top plan view of a slipper embodying my new design;

Fig. 2 is a side view of the same;

Fig. 3 is a front view of the same; and

Fig. 4 is a rear view of the same.

I claim:

The ornamental design for a slipper, substantially as shown.

ISRAEL GARON.
